METHOD AND MEANS FOR CONTROLLING THE MOISTURE CONTENT OF PAPER OR OTHER MATERIAL.

Application filed October 24, 1927. Serial No. 228,219.

This invention relates to the automatic control of the amount of one or more constituents in a product continuously manufactured or treated, and where close uniformity is desirable, such for example, as in the manufacture of paper. While all of the various constituents of the web of paper should be maintained uniform and the present invention in its broader aspects is not limited to any one, this invention more specifically relates to the control of the moisture content of paper or other continuously manufactured or treated product.

The nature of this invention will be better understood by considering at greater length one particular example illustrating the general problem with which it has to do and showing its more specific adaptation to the automatic control of moisture content of paper. Assuming, therefore, that moisture content only is to be controlled, and that the material is coming off from a drier, the drying action of which is dependent in amount upon the amount of steam supplied thereto for heating drying elements, if the steam controlling valve is set at just the proper amount to deliver the material at exactly the desired moisture content, nothing happens. If now conditions change so that the moisture content departs somewhat from that desired, the steam valve is actuated automatically in a corrective manner, small moisture deviations requiring small valve corrections and large deviations requiring correspondingly larger valve corrections. A suitably adjusted proportionality between steam valve response and moisture deviation is sufficient alone to hold the moisture between more or less close limits, but is subject to an inherent error in that except for hand adjustments, one position of the valve can be had only through one corresponding moisture content so that valve adjustments involve changes in moisture setting of the instrument, possibly small, but certainly undesirable. Moreover, where it is not possible or convenient to employ a positive mechanical connection between the moisture indicator and the valve, as is usually the case, there is certain to be a drifting, because of imperfect synchronism, of the correspondence between a particular indication and a particular valve setting. As a result the instrument may, particularly

after an extended time of operation with its cumulation of errors, tend to hold the moisture content at a different value from that desired and for which the instrument was initially adjusted. Where fluctuations of drying requirements are unusually wide or erratic, it becomes necessary to deal with wide instead of narrow ranges of steam valve position and with large instead of small changes in the temperature of the heavy masses of the driers, entailing large time lags and considerable tendencies to overrun the temperatures at the working faces of the drying mechanism and consequent degree of dryness aimed at, on account of accumulative effects and irregular distribution of temperatures during what may be termed thermal acceleration and deceleration. With such severe conditions a simple proportionality between instrument responses to changes from normal and displacement of the steam valve controlled thereby from its normal, is not in itself enough to give the best regulation of moisture of which the method is capable and under such conditions also the drifting tendency is much increased.

The present invention, therefore, has to do with modifications and refinement which are particularly adapted to deal with such extreme conditions as well as with less severe conditions in order to obtain the closest possible regulation. To this end I provide a controlling instrument which, no matter what its correcting motions may be, acts or tends to act to return the corrective portion of the mechanism to a position corresponding to that where the material has exactly the desired moisture content desired and quite irrespective of any particular valve setting. For the purpose of illustration only, and not of restriction, the invention is shown herein as applied to an automatic moisture controlling mechanism for a paper machine, the mechanism being of a type more particularly described and claimed in an application for patent by Albert Allen and John G. Callan, Serial No. 228,220 filed October 24, 1927, for apparatus for controlling moisture content of paper or the like, and which is shown in the accompanying drawings.

Referring to these drawings, Figure 1 is a somewhat diagrammatic view showing a portion of a paper drier and a

calender stack with automatic mechanism for controlling the steam supply to the drier.

Figure 2 is an elevation of a steam valve mechanism, the casing cover being removed.

5 Figure 3 is a section on line 3-3 of Figure 2.

Figure 4 is a detail shown in Figure 3 but drawn to a larger scale.

10 Figure 5 is a somewhat diagrammatic perspective of a control mechanism for the valve actuating mechanism.

Figure 6 is a section through the hygrometric device.

Figure 7 is a wiring diagram.

15 Referring first to Figure 1, A represents a part of the usual drier stack for the paper machine, being either the last portion of the main stack for a machine without means for top sizing, or the last of the "small 20 stack" beyond the size tub in machines so equipped. At B is shown a calender immediately following the last drier. The paper coming from the calender B passes in responsive relation to a hygrometric device 25 shown in detail in Figure 6 at C, as shown this device having a hygrometric element responsive to the moisture of the paper after it leaves the calender. It might, however, be placed in responsive relation to the paper 30 after its initial drying and before it is passed through the top size tub in the production of top sized papers, or it might be placed at any point in the paper machine, paper-coating machine, or the like, at which 35 the paper or other material should have a determinate moisture content arising from, or residual from, thermally controllable processes or operations preceding the measuring point.

40 The hygrometer C is shown as connected to an instrument D which contains parts of certain high frequency circuits as shown diagrammatically in Figure 7. In a portion of these circuits is placed a recording and controlling instrument E shown in detail in Figure 5 and there may also be in these circuits an indicating instrument F of the thermometer type. The instrument E controls the supply of electrical energy to a valve- 45 actuating and controlling mechanism at H which is shown in detail in Figures 2, 3 and 4.

45 The hygrometric device may be of any suitable type, but as herein shown more particularly in Figure 6 is that described and claimed in the application for patent of Albert Allen, Serial No. 152,126, filed December 2, 1926, for hygrometers. It comprises an open sided elongated box or casing 50 having at one end an enlarged box-shaped portion 11 in which are positioned the plates 12 and 13 of a book type electrical condenser. As shown the plate 12 is supported from an insulating sheet 14 fixed in a portion of the box and the plate 13 is provided with a knife

edge bearing portion 15. The knife edge portion 15 is held to its bearing 16 as by means of one or more springs 17 and it is normally held rocked toward the plate 12 as by means of the spring 18. An adjustable 70 stop screw 20 is shown as threaded through the end portion of the box-shaped portion 11 and passes through suitable holes through the plate 12 and the insulation 14, its inner end serving to limit the approach of the 75 plate 13 toward the plate 12. The edge of the plate 13 remote from the knife edge 15 and adjacent to the open side of the container 10 has fixed thereto as at 21 one end of a hygrometric ribbon 22. This ribbon may 80 be of any suitable form, one which has been found satisfactory in service being made of artificial silk as by the viscose process. The opposite end of the ribbon passes about a fixed rod 24, about a rod 25 which is adjust- 85 able by means of the adjusting bolt 26, and then to and about an anchoring rod 27. The ribbon is thus held under some tension close to the open side of the container over which the paper passes. The best results are usu- 90 ally obtained when the side walls of the container are extended laterally on either side of the open sided portion. When so constructed the paper may be passed over the device without actually contacting there- 95 with and yet enclose a body of air circulated by the movement of the paper in intimate contact with the paper surface and the hygrometric material so as to produce the desired response in the hygrometric material 100 in apparently as satisfactory a manner as where the paper is drawn over the hygrometric device in contact with the casing.

Changes in the moisture content of the paper passing over this device cause corresponding proportional changes in the moisture content and consequently in the length of the ribbon, thus changing the spacing between the condenser plates 12 and 13 and changing the capacity of the condenser 105 formed by these plates. The sensitivity of this device may be regulated by adjusting the initial spacing between the condenser plates, the further the plates are initially placed, the less sensitive being the indication, as an 110 equal movement of the plate 21 under such circumstances causes less change in capacity than where the plates are closer together. It will thus be seen that the moisture content of the paper passing over the hygrometric 115 device controls the capacity of the condenser. This capacity and changes of capacity may be accurately and promptly recognized by suitable apparatus, such for example as that disclosed in the Allen application for patent 120 Serial No. 166,705, filed February 8, 1927, for means for measuring characteristics of material.

An apparatus of this general type is disclosed somewhat diagrammatically in the 125

wiring diagram of Figure 7 which includes the instruments D, F and E. The particular circuits shown in this Figure 7 are disclosed and claimed in the application for patent of 5 Robert F. Field, Serial No. 227,694 filed October 21, 1927 for oscillatory circuits and method of compensating for voltage changes impressed thereon. In general, it may be stated here that they comprise a primary os- 10 oscillatory circuit indicated at M coupled as by the capacity coupling 30 with a secondary oscillatory circuit N. The primary oscillatory circuit is shown as energized through a transformer 31 from an alternating current 15 source and contains an electron tube 32, together with various capacitances and inductances so placed that the circuit M oscillates at a desired frequency. Any suitable oscillatory circuit can be used, but that shown is 20 particularly suitable for the purpose, in that it may be made to inherently compensate for quite considerable changes of voltage im- 25 pressed on the transformer 31. The secondary circuit N is provided with capacitances and inductances and includes as a part of the capacitance that represented by the hygro- 30 metrically controlled condenser plates 12 and 13. It is so adjusted relative to the primary circuit M that its free period of oscillation 35 is slightly higher than that of the primary circuit M, but is sufficiently near resonance therewith so that a current flow is induced therein dependent in amount on its nearness to resonance with the primary circuit M. 40 Under such conditions the changes in capacitances of the plates 12 and 13 bring the natural period of the secondary circuit closer to or farther from resonance in accordance with the changes of spacing between the 45 plates due to moisture changes in the ribbon and vary the current flow in the secondary circuit correspondingly. These changes in current flow may be recognized, as by means of the thermo-ammeter F, the parts being so arranged as more fully disclosed in the Al- 50 len application Serial No. 166,705 that a mid- position on the scale of the thermo-ammeter indicates a desired condition, which in the present instance represents a predetermined moisture content of the sheet material.

Supplementary to, or used in place of the thermo-ammeter F, is the instrument E shown in detail in Figure 5, to which current in amount dependent on the moisture response of the hygrometric device is conducted through the wires 40 and 41. These wires lead to a milli-voltmeter of the well known d'Arsonval type having a needle 50 carried by a moving element 51 mounted in a familiar manner between the poles of the permanent magnet 52. The current thus causes deflection of the needle 50 in proportion to the moisture content of the material, the apparatus being so adjusted that the needle 50 takes 55 a midscale position when the response of the

hygrometric device indicates the desired moisture content of the paper, the mechanism being also adjusted as to sensitiveness so that any deviation of moisture which may be expected will be insufficient to move the 70 pointer 50 off scale in either direction. This milli-voltmeter apparatus is used to control a current supply to a relay at G in such a manner as to control the valve-actuating mechanism at H, as will later more fully appear. 75

Usually besides serving as an indicator of moisture content, the instrument E will also be so designed as to record the moisture content and the instrument herein illustrated is 80 adapted for both purposes.

For the purpose of recording, as well as for actuating the mechanism H, means are provided for depressing the needle 50 at suitable time intervals. For this purpose an arcuate 85 depressor bar 55 is shown which bears upon a conical roller 56 preferably of light, thin silver, on an insulating wire, which is journaled on the needle 50 but insulated from it. This depressor bar 55 is carried by a parallel motion mechanism so as to move vertically in a direction parallel with the swinging axis of the needle. For this purpose a shaft 57 is journaled in suitable standards at the back of the instrument and has fixed thereto adjacent to opposite ends, arms 58 and 59. Pivoted at points beneath the arms 58 and 59 and in vertical alinement with the shaft 57 are, similar arms 60 and 61. The forward ends of the arms 58 and 60 and 59 and 61, respectively, are pivotally connected to the brackets 62 and 63, respectively, to which opposite ends of the depressor bar 55 are fixed. At suitable time intervals the shaft 57 is rocked to move the depressor bar downwardly and then upwardly. For this purpose the shaft 57 is provided with a crank arm 65, connected through a link 66 to a suitable actuating cam 68 of a mechanism at 67, herein shown as a synchronous electric motor clock of any suitable type. 100 105 110

Beneath the needle 50 is shown positioned a recording paper sheet or strip 70 which passes over a suitable driving roll 71 and beneath a ribbon 72, preferably of carbon paper, which passes about end rolls beyond opposite 115 edges of the paper 70, one of these rolls being shown at 73. This roll 71 is rotated slowly to effect a progressive feed of the record sheet and for this purpose it is shown as fixed to a shaft 74 having a sprocket wheel 75 thereon which may be driven as by means of a chain 76 from the clock motor 67. In order that a fresh part of the surface for the carbon paper may be presented beneath the needle at each printing actuation thereof, the roller 73 over which the carbon strip passes is shown as connected for rotation by the shaft 74, spiral gears 77 and 78 on the shaft 74 and the shaft 79 which carry the roll 78 being shown as employed for this purpose. 120 125 130

It is desirable that the needle 50 be given a quick downward motion so that it may strike upon the carbon paper a sharp quick blow in order to produce the desired mark on the record sheet and then relieve the needle from contact with either bar or paper. For this purpose means are provided for snapping the needle downwardly to make a sharp blow and then retract it somewhat from the carbon paper, even though the depressor bar may be holding the roll 56 in its downward position after the recording blow has been struck. For this purpose the bar 58 has pivoted thereon a bell crank lever 80. One arm 81 of this lever, as shown, is connected through a spring 82 to a bar 83 which is positioned above the needle 50 forwardly of the depressor bar 55. A spring 85 acting on the arm 84 of the lever holds a pin 86 on the lower end of this arm against the teeth of a ratchet wheel 87 which is held from rotation in one direction by a spring pressed pawl 88. As the bar 58 is swung downwardly to depress the depressor bar the pin 86, riding on the inclined face of one of the teeth of the ratchet wheel 87 moves or holds the arm 81 upward until such time as the pin 86 rides over the apex of the ratchet tooth, whereupon the spring 85 immediately acts to snap the lower end of the arm 84 rearwardly, this sharply depressing the arm 81 and bringing the bar 83 down on the needle 50 with a sharp blow. The inertia of the bar 83 is sufficient to produce an overthrow to an extent sufficient to cause the needle to strike a sharp blow on the printing strip and the record paper, the spring 82 then acting to lift the bar 83 slightly so that the needle 50 may retract from the carbon ribbon and the bar 83 from the needle. It should be understood, of course, that the bar 83 has a similar actuating mechanism on each end.

When the depressor bar moves the needle 50 downwardly, it brings the roller 56 down on to a sector member 850. This member carries on its upper face an arcuate conducting strip 860 extending its entire circumference and a pair of arcuate conductor strips 870 and 880 parallel to the strip 860 and spaced apart centrally. As the roller 56 is brought down, therefore, it makes contact with the strip 860 in whatever angular position the needle 50 may be. If it is in the central position, it comes down between the strips 870 and 880 and makes contact with neither. If, however, the needle when it is depressed is away from the central position and thus denotes a departure from the desired moisture content of the paper, it connects electrically the contact of the strip 860 with one or the other of the strips 870 and 880. When the contact is made between the strips 860 and 870 electrical connections are made through the relay G to the valve-actuating mechanism H, as will later appear, in a manner to decrease the heating effect of the drier, but

when the contact is made between the strips 860 and 880, the mechanism H is operated in the reverse direction to increase the heating effect of the drier.

The control of the valve-actuating mechanism is designed to be effected whenever the needle 50 moves away from its central or normal position and is depressed, and is so designed that proportionality between the deflection of the needle from this central position and the valve response is secured, this proportionality being effected by a follow-up mechanism. The follow-up mechanism illustrated is as follows: The segment 850 is mounted to turn about the axis of the meter 51 and as shown is provided with worm teeth on its circumference with which meshes a worm 90 carried by a shaft 91. At one end of the shaft 91 is fixed a beveled gear 92 and in axial alignment with the shaft 91 is a shaft 93. The shaft 93 carries a similar beveled gear 94 facing oppositely to the gear 92 and between the gears 93 and 94 are positioned the beveled pinions 95 and 96 journaled on stub shafts on a spider 97. This spider is journaled at opposite ends on the shafts 91 and 93. This particular connection between the shafts 93 and 91 is for a purpose which will presently be described. The follow-up mechanism is actuated by rotation of the spider 97, which through the rotation of the pinions 95 and 96 by their engagement with the gear 94, turns the gear 92 and rotates the shaft 91. This rotation of the spider is accomplished by means of a sprocket wheel 100 carried by the spider and which is connected through a chain 101 with a reversing clock motor 102. As shown this clock motor has a wire 103 connected to one side of the single phase alternating current supply and two field terminal wires 104, 105. The motor fields are independent, energization of one causing rotation of the clock in one direction and energization of the other causing its rotation in the reverse direction. The wires 105 and 104 lead to the relay G. As shown in the upper left hand corner of Figure 5, this relay is provided with an arm 107 which may be rocked in either direction from a central neutral position to which it is biased, to close connections between the wire 103 and either of the wires 104 and 105, —which connection being determined by a pair of solenoids 110, 111. Each of these solenoids has one end connected to the wire 103 leading from the opposite power line 301 and each has its other end connected to one of the contact segments, solenoid 110 being thus connected electrically with segment 880, and solenoid 111 with segment 870. The segment 860 is long enough to parallel both 870 and 880 and is connected electrically to one side 300 of the power line. Thus, if when the needle is depressed it is in mid-position,

- neither of the solenoids 110 or 111 will be energized and the switch arm 107 will be in a neutral mid-position where it is yieldingly held and the motor 102 unenergized.
- 5 If, when the needle is depressed electrical connection is made between the strips 860 and 870, the solenoid 110 is energized, thus closing the motor circuit through the wire 105 and causing the clock motor to rotate in a 10 direction to turn the sector 850 to the left, this being done so long as the needle when in its depressed position bridges the strips 860 and 870. When the sector is moved sufficiently to cause the needle when it is depressed 15 to fail to contact with the strip 860, the clock motor 102 becomes de-energized and no further motion of the sector by this motor occurs. At the same time that this motor 102 is energized, a controlling or adjusting 20 mechanism of the valve-actuating mechanism H is operated to change the valve setting at a speed proportional to that of motor 102 and in a correcting direction. If the needle 50 should, when it is depressed, be on 25 the opposite side of the central point of the sector 850 and so make electrical connection between the strips 860 and 880, solenoid 111 will be energized, thus closing the circuit through the wire 104, causing the motor 102 30 to rotate in the opposite direction and moving the sector 850 to the right, such action taking place as long as the circuit is closed between the strips 860 and 880. At the same time the valve-actuating mechanism is operated 35 in the reverse direction to effect a corresponding controlling action of the valve.
- The valve-actuating mechanism, as herein shown more particularly in Figures 1 to 4, comprises a constantly running motor 120 40 which actuates through a suitable reducing gear, a crank disk 121. This is connected by means of the connecting rod 122 to an arm 123, which is thus constantly rocked on a shaft 124 as a fulcrum. It carries a pair of 45 solenoids 125, 126. These solenoids are provided with cores 127 connected to an arm 128 fulcrumed at 129 on the arm 123. Also fulcrumed at 129 is a double pawl 130 normally held in central position relative to the 50 arm 128 as by means of the two leaf springs 131 engaging opposite faces of a stem portion 132. Arm 128 is normally held in central position relative to solenoids 125 and 126 as by coil springs. By energization of either of the 55 solenoid magnets 125 and 126, the arm 128 may be rocked in either direction thus to bring one or the other end portions 134, 135 of the pawl 130 into operative relation to a reversible ratchet wheel 136 fixed to the shaft 124. 60 The outer end of the solenoid 125 is connected to the wire 105 and the outer end of the solenoid 126 to the wire 104, the inner end of these windings being connected together and to the line 300. When the relay G is operated to 65 connect the wire 103 to the wire 105, the sole-
- noid 125 is energized and the pawl end 134 is brought into operative position, whereupon at each oscillation of the arm 123 by the motor 120 the ratchet wheel 136 is rotated in one direction, while if the wire 104 is connected 70 to the wire 103, the solenoid 126 is energized and the end 135 of the pawl is brought into operative relation, whereupon oscillation of the arm 123 rotates the ratchet wheel 136 in the opposite direction. The shaft 124 to 75 which the ratchet wheel 136 is fixed extends outwardly of the casing of the apparatus H and carries a sprocket wheel 140 over which passes a chain 141, this chain leading about a sprocket wheel 142 (see Figure 1) journaled 80 on a stub shaft at the end of a lever 143. On this lever rides a weight 144 which is connected to one side of the chain 141 so that on rotation of the shaft 124 in either direction the weight 144 is caused to move lengthwise 85 of the lever 143. This lever 143 is shown as controlling a steam valve. The steam valve is indicated at 145 and is shown as of the diaphragm controlled pressure regulating type, whereof the loading of the diaphragm and 90 consequently the pressure that it will determine, is fixed by the position of the weight 144. The lever 143 is shown as fulcrumed at 155 on a bracket 156 carried by the exhaust pipe 157 so that the position of the weight 95 determines the load on the diaphragm. In accordance with a common practice this pressure regulating valve is shown as on the line leading from the paper machine engine to the condenser or the free exhaust. It puts more 100 or less back pressure on the exhaust from the engine and thereby determines the pressure and hence the temperature of the steam supply through a branch pipe 150 leading to drier cylinders of which one is shown at 151. It 105 will be understood, of course, that any other suitable mechanism for controlling the supply of the heating agent to the drier might be used, it being only necessary that this supply should be controlled and in the right direction 110 in accordance with the action of the mechanism at E.
- In order that the weight 144 may not by any chance be moved too far in either direction on the lever, provision may be made by which 115 the electrical connections for moving it in either direction will be interrupted when the weight is at the desired extent of travel in that direction. Such a mechanism is shown in Figures 3 and 4. Referring to these figures, it will be seen that the shaft 124 carries at its upper end a threaded portion 160 on which 120 rides a nut 161 held between a pair of jaws 162 at one end of one arm of a bell crank lever 163. The opposite arm of this bell crank 125 lever has fixed thereto a pair of switch elements 164 and 165, which, as shown, may pass between pairs of spring contact members 166 and 167, respectively. The spring contact members 166 are interposed in the wire con- 130

nection 105 and the spring contacts 167 are interposed in the wire connection 104. The switch elements 164, 165 are preferably of the quick break type, so as to minimize the 5 arcing between them and the spring contacts 166, or the spring contacts 167, when the corresponding elements 164 or 165 are moved out of contacting relation therewith. As shown the elements 164 and 165 each comprise a bar 10 168 having pivoted thereto at 169 a member 170. This member 170 normally lies against one face of the bar 168 and is held in such position by any suitable spring means, but it may be swung away from bar 168 by pressure exerted thereon until the stop 171 on the 15 opposite side of its pivot contacts with the base portion of the bar 168. Thus as either of these switch elements is moved out from between its corresponding spring contact 20 jaws, the member 170 is retained between the 25 jaws while the member 168 passes therebeyond. When the portion 171 contacts with the lower part of the elements 168, so that no more pivotal motion is permitted, the switch element 170 snaps free from between the 30 spring contact jaws as the bell crank lever 163 continues to move, springing back to its normal position against the bar 168. The parts are so designed, therefore, that whenever the 35 solenoid 125 is actuated, the bell crank lever is moved gradually in a direction tending to break the connection between the spring contacts 166 and the element 164 and this occurs before the weight has been moved too far in its direction of sliding movement. Similarly the contact is broken in the wire connection 104 whenever the weight moves to its extreme position in the opposite direction.

It will be noted that the mechanism E is 40 operatively connected to the valve controlling mechanism by electrical means. It is found in practice that where a direct unvariable mechanical connection can not be conveniently used, as on account of inaccessibility of the valve, or for other reason, and an 45 electrical mechanism is used, there is certain to be more or less deviation from exact synchronism between the operation of the mechanism E and the valve controlling mechanism, 50 and as this lack of precise synchronism may be cumulative over long periods, in time any one setting of the instrument needle may not correspond to the same valve setting at which the mechanism was originally adjusted to 55 operate, and consequently the moisture conditions which the mechanism may tend to maintain constant, are not those for which the mechanism was originally set.

While it is not difficult to reset the valve 60 mechanism by hand, as by throwing out the automatic control, as by means of the switch 180 (Figure 1), the relay mechanism being then actuated by hand as desired as by means of the knob 181 fixed to the pivot of the switch 65 drum 107, it is not always desired to do this,

and means are therefore provided according to this invention by which there is a tendency of the mechanism to re-establish periodically or concurrently with other actions an equilibrium relation between instrument-needle indication and valve-setting, and at the same time to bring the needle back to its initial setting for the desired moisture content on every departure therefrom quite regardless of what position the valve may occupy. For 70 this purpose, as well as another which will later appear, as shown, the shaft 93, which is in alinement with the shaft 91, has fixed thereto a sprocket wheel 200 which is connected by a sprocket chain 201 to the drive sprocket of 80 a reversible electric clock motor 202 similar to the clock motor 102. The wire 203 leading from the common field point of this motor leads to the side 300 of the energy supply. The other field coil terminals 204 and 205 85 are connected respectively to the upper arcuate conducting strips 206 and 207 arranged back of the pivot point of the needle 50, adjacent ends of these conducting strips being spaced apart as shown at 208. Spaced beneath the strips 206 and 207 is a continuous strip 209 insulated therefrom by the supporting block 210 in which these conducting strips are fixed. Between the upper and lower sectors rides a pin 211 carried by the sector 850. 90 When the pin 211 is in its mid-position, this representing also the normal mid-position of the sector 850, the pin 211 rides on the strip 209, but is out of contact with both the strips 206 and 207. On the movement of the sector 95 100 850, however, through a follow-up motion occasioned by actuation of the motor 102, the pin 208 makes electrical connection between one or the other of the strips 206 and 207 and the continuous strip 209, thus energizing the 105 motor 202, the strip 209 being shown as connected to the opposite side 301 of the current source from that of the wire 203. Operation of the motor 202 thus turns the shaft 93 in a direction such as to return the segment 850 110 to its normal mid-position, but at a rate much slower than that of the follow-up motion produced by actuation of the clock motor 102. Whenever the sector 850 is displaced from 115 its mid-position in either direction, the motor 202 is energized in a manner to tend to return the sector to its mid-position. This returning tendency is exercised whether the depressor bar is down or up, whereas the follow-up motion is produced only when the depressor bar 120 is down, since it is only at this time that the roller 56 is brought into electrical connection with the conducting strips 860 and 870 or 880 carried by the segment 850. This returning action of the motor 202 is thus accomplished 125 irrespective of any follow-up motion, the actual resultant motion of the sector being the algebraic sum of the two at any instant. There is thus no chance for the mechanism to come to equilibrium with the needle 50 of 130

center of the scale and at an undesired moisture content, since it is always returned when displaced therefrom in either direction whether or not there is any resultant change in the setting of the steam valve.

The utility of the mechanism for returning the segment 850 relatively slowly to its mid-position whenever displaced therefrom may be more readily understood by certain detail 10 considerations. The follow-up motion which moves the sector 850 away from the central position in the direction of movement of the needle when the needle is displaced from its central position would ordinarily bring about 15 a new condition of equilibrium at a new position of the contacts 870 and 880 and consequently a new position of the needle 50 intermediate therebetween, and consequently, in turn, at a new equilibrium value of dryness 20 which might be only a little removed from that desired, but which would still not be exactly the predetermined dryness. This correction movement which brings the contacts on the sector 850 back to the central position 25 where deviation of the needle will set up corrective actions in the drier, prevents any such equilibrium being established except at predetermined dryness desired. This return to normal contact position may be at a predetermined rate consonant with the rate at 30 which in the circumstances the dryness can or should return to normal without entailing such heat storages or discharges in the drying parts as will cause the temperature correction of this part to overrun and set up 35 fluctuations of dryness consequent thereupon. The rate of return can be controlled wholly or partly by rate of change of the driers or by the dryness of the paper or by time alone 40 as may be desired. In any event it is much slower than the follow-up movement. The time of return may be controlled by any suitable means such as by the use of change gears on the clock driving mechanism.

In paper machine regulation the rate of movement of the sector 850 back to normal condition will usually be intended to be correlated directly with the rate at which the heavy metal driers heat or cool when the heat 45 supply to them is changed. For example, suppose moisture normal at 7% changes to 7½% and the instrument needle 50 swings to the right by a corresponding amount causing the valve 145 to be operated, to increase 50 the heat and move the sector 850 with its central point opposite the new position of the needle. Suppose now that the new heat supply is just enough to maintain equilibrium at 7% moisture under the new working conditions and therefore more than enough to hold 55 7½%. At first the added heat will go to heating up the inner parts of the driers and then to the outer working surfaces and will increase the drying of the paper, cut down

the moisture of the felt against which the paper passes, and eventually if the valve be left unchanged, equilibrium will be reached at 7% moisture of the paper. The proper speed of the motor 202 will then be that at which the sector 850 will be brought back 70 toward the 7% mid-position just so fast that the mid-position of the sector will remain under the needle as the needle returns back to its 7% mid-position. In point of fact a movement exactly meeting this requirement 75 will not be a uniform one since the rate of change of drier temperature is faster at first than during its stage of final approximation to its new temperature. However, a fair mean value can be fixed upon that will serve 80 all practical purposes and usually it is such that will bring the sector back to its proper mid-position at a time substantially the same as or a little less than the temperature lag in the machine.

Not only does this mechanism correct the departures from initial relationship between instrument and valve setting due to the drift previously defined between the valve and follow-up movement, since this accumulated 90 drift is periodically canceled through re-establishment of a correct setting of the apparatus, but it also prevents the apparatus from assuming a new equilibrium point at a moisture content of the paper slightly different 95 from that desired.

Having thus described this invention, together with certain mechanism by which the results sought may be obtained, it should be evident to those skilled in the art that various changes and modifications might be made without departing from the spirit or scope of this invention as defined by the appended claims.

I claim:

1. In a paper machine, a device responsive to the amount of certain constituents of the paper coming from such machine, means actuatable to vary the amount of such constituents, means for actuating said varying means controlled by variations in the response of said device from that response indicating a desired normal amount of such constituents, and means tending to return said actuated means when displaced therefrom to a condition corresponding to normal response for said device to the desired amount of said constituents.

2. In combination, a drying mechanism, means for controlling said mechanism, a device responsive to moisture of material delivered from said mechanism, means controlled by variations of response of said device from that response indicating a desired normal moisture content of said material for actuating said controlling mechanism, and means tending to return said actuating means when displaced therefrom to a condition cor-

responding to the response of such device to normal moisture of said material.

3. In a paper machine, a device responsive to the amount of certain constituents of paper coming from such machine, means actuatable to vary the amount of such constituents, means rendered periodically operative for actuating said varying means in corrective direction when the response of such device is different from the response due to a normal desired amount of such constituent, and means tending to return said actuating means when displaced therefrom to its condition corresponding to normal response of said device to the desired amount of such constituents.

4. In combination, a drier, a valve for controlling the supply of a drying agent to said drier, a device responsive to moisture content of material coming from said drier, means controlled by variations in the response of said device from that indicating a desired normal moisture content of such material to change the opening of said valve in a correcting direction, and means tending on each displacement therefrom to return said changing means to its condition corresponding to normal response of said device to the desired moisture content and to complete such return only after a time interval large compared with the time of such displacement.

5. In a paper machine, means actuatable to vary the amount of certain constituents of paper coming from said machine, a device responsive to the amount of such constituents, means controlled by variations in the response of said device from that indicating a desired normal amount of such constituents to actuate said varying means in a corrective direction, and means tending on each displacement therefrom to return said actuating means to its condition corresponding to normal response of said device to the desired amount of said constituents and to complete

such return only after a time interval large 45 compared with the time of such displacement.

6. In combination, drying mechanism, a device responsive to moisture content of material coming from said mechanism, means for varying the drying effect of said mechanism, means for controlling said varying mechanism, said controlling means having a movable element the position of which is controlled by the response of said device and follow-up means relative to which said device moves, means for actuating said varying means in correcting direction on departure of said element from a determined point of said follow-up means, means actuatable on each such departure to move said follow-up means 60 in a direction to bring said point toward said element, and means acting during a period longer than that of the movement of said follow-up moving means to return said follow-up means to a central position where said 65 point represents an element position corresponding to the desired moisture content of the material.

7. In a mechanism for controlling the moisture content of material coming from a drier in which deviation of moisture content from that desired causes movement of an element from a normal position relative to a follow-up member, such movement relative to said member changing the rate of supply of 70 a drying agent to the drier and causing movement of said member toward said element to cause the amount of rate change to be proportional to the extent of departure of the moisture from the desired amount, that step which 75 comprises moving said member on deviation in either direction from a central normal position toward said central normal position during a period longer than its follow-up motion away from such position. 80

In testimony whereof I have affixed my signature.

HERBERT. L. BONE.

CERTIFICATE OF CORRECTION.

Patent No. 1,722,655.

Granted July 30, 1929, to

HERBERT L. BONE.

It is hereby certified that the assignee in the above numbered patent was erroneously described and specified as "Atlantic Precision Company", whereas said name should have been described and specified as "Atlantic Precision Instrument Company", as shown by the records of assignments in this office; and that the said Letters Patent should be read with this correction therein that the same may conform to the record of the case in the Patent Office.

Signed and sealed this 20th day of August, A. D. 1929.

responding to the response of such device to normal moisture of said material.

3. In a paper machine, a device responsive to the amount of certain constituents of paper coming from such machine, means actuatable to vary the amount of such constituents, means rendered periodically operative for actuating said varying means in corrective direction when the response of such device is different from the response due to a normal desired amount of such constituent, and means tending to return said actuating means when displaced therefrom to its condition corresponding to normal response of said device to the desired amount of such constituents.

4. In combination, a drier, a valve for controlling the supply of a drying agent to said drier, a device responsive to moisture content of material coming from said drier, means controlled by variations in the response of said device from that indicating a desired normal moisture content of such material to change the opening of said valve in a correcting direction, and means tending on each displacement therefrom to return said changing means to its condition corresponding to normal response of said device to the desired moisture content and to complete such return only after a time interval large compared with the time of such displacement.

5. In a paper machine, means actuatable to vary the amount of certain constituents of paper coming from said machine, a device responsive to the amount of such constituents, means controlled by variations in the response of said device from that indicating a desired normal amount of such constituents to actuate said varying means in a corrective direction, and means tending on each displacement therefrom to return said actuating means to its condition corresponding to normal response of said device to the desired amount of said constituents and to complete

such return only after a time interval large 45 compared with the time of such displacement.

6. In combination, drying mechanism, a device responsive to moisture content of material coming from said mechanism, means for varying the drying effect of said mechanism, means for controlling said varying mechanism, said controlling means having a movable element the position of which is controlled by the response of said device and follow-up means relative to which said device moves, means for actuating said varying means in correcting direction on departure of said element from a determined point of said follow-up means, means actuatable on each such departure to move said follow-up means 60 in a direction to bring said point toward said element, and means acting during a period longer than that of the movement of said follow-up moving means to return said follow-up means to a central position where said 65 point represents an element position corresponding to the desired moisture content of the material.

7. In a mechanism for controlling the moisture content of material coming from a drier in which deviation of moisture content from that desired causes movement of an element from a normal position relative to a follow-up member, such movement relative to said member changing the rate of supply of 70 a drying agent to the drier and causing movement of said member toward said element to cause the amount of rate change to be proportional to the extent of departure of the moisture from the desired amount, that step which 75 comprises moving said member on deviation in either direction from a central normal position toward said central normal position during a period longer than its follow-up motion away from such position.

In testimony whereof I have affixed my signature.
